UNITED STATES PATENT OFFICE

2,588,986

CONNECTION FOR REVERSIBLE IRON CORDS

Donald Leroy Reynolds, Independence, Mo.

Application July 28, 1950, Serial No. 176,383

3 Claims. (Cl. 219—25)

1

This invention relates to electric sadirons, and more particularly to the attaching means for attaching a flexible conductor cord to the sadiron.

Heretofore it has been the practice to attach an electric conductor cord to the rear or side of the sadiron and in some instances, to attach the electric conductor cord so that it may be rotated from one side to the other. The disadvantage of the cord extending from the rear or sides of the iron is dragging of the cord over the ironing board which interferes with the ironing operation. Furthermore in cords extending from the right side of the sadiron, it is very awkward for a left-handed person to use such iron or vice versa. With such irons the cords are very likely to become broken and worn in a short time due to bending and strain.

It is the principal object of the present invention to provide a sadiron having a handle portion with means whereby the electric conductor cord may be attached from either side thereof at the will of the operator.

Other objects of the present invention are to provide a slot in the handle for an electric insert or plug adapted to receive the electrical connection of the cord through an opening in either side of the handle; to provide for removable attachment of the electric cord terminal to either side of the handle, and to provide a device of this character simple, economical to manufacture, and efficient in operation.

In accomplishing these and other objects of the invention, I have provided improved details of structure, the preferred forms of which are illustrated in the accompanying drawings wherein:

Fig. 1 is a perspective view of a sadiron embodying the features of my invention.

Fig. 2 is a fragmentary view of the rear portion of the handle showing the connecting means in disassembled relation.

Fig. 3 is a cross-sectional view through the rear portion of the handle particularly illustrating the socket contact elements.

Fig. 4 is a cross-sectional view taken on line 4—4, Fig. 3.

Referring more in detail to the drawings:

1 designates a sadiron embodying the features of my invention comprising a body portion 2 and a sole plate 3 and a handle 4 having a generally upright portion 5 at the rear thereof. The body portion 2 contains a heating element (not shown) as is the usual practice.

The handle and upright portion thereof is made of a non-heat conductive or electric insulating material such as rubber, plastic or other

2

suitable material, and is provided with a recess 6 extending inwardly from the rear face thereof as illustrated in Fig. 2. The rear portion of the handle is secured to the top plate 7 of the body portion by screws or the like 8 and the plate is provided with an opening 9 through which an electric connection 10 extends to the heating element.

A removable insert or plug 11 is provided for engaging in the recess 6 and is retained therein by a set screw 12 as best illustrated in Fig. 3. The rear portion of the handle being provided with a threaded opening extending into the recess portion of the upright member and the upper portion of the insert having a bore 13 into which the head 14 of the screw is embedded as best illustrated in Fig. 3. The insert 11 is provided with socket contact elements 15 and 16 having arms 17 and 18 to which prong contacts 19 and 20 of the connection 10 are attached. The socket contact elements are substantially circular and extend to the side edges of the removable plug 11 forming a socket 21 and 22 on each side of said plug.

The upright portion 5 of the handle is provided with laterally extending openings 23 and 24 provided with threads as indicated at 25 and 26 (Fig. 2) terminating in the recess 6 in said upright member.

A cord 27 is provided for supplying current to the heating element having the usual connection 28 for attachment to a wall socket or the like. The opposite end of the cord 27 is provided with a connection 29 of a non-heat conducting or insulating material having prongs 30 and 31 provided with terminals 32 and 33 to which the ends 34 and 35 of the wires of the cord are attached. The connection 29 is provided with an annular flange 36 and a reduced portion 37. Adapted to be sleeved over the cord 27 is a sleeve member 38 having a socket 39 engaging over the reduced portion 37 when the connection is attached to the handle of the iron. The end of the sleeve member 38 opposite the socket is provided with an

annular groove 40 and a sleeve 41, preferably made of rubber or the like, engaging over the cord 27 and is also provided with a socket 42 having a lift 43 adapted to engage in the annular groove 40 of the sleeve member 38. The sleeve member 38 and the sleeve 41 are rotatable and slidable on the cord 27 and the outer periphery of the sleeve member 38 is provided with threads 44 engaging with the threads 25 and 26 on either side of the upright portion 5 of the handle 4.

In the use of a device constructed and assem-

bled as described when the iron is desired to be used by a right-handed person, the connector 29 of the cord 27 is inserted in the threaded opening 24 of the handle and the prongs 30 and 31 engage in the sockets 21 and 22 of the insert 11. The sleeve member 38 is then rotated on the cord so that the threads will engage the threads 26 of the opening 24 and the contacting element and the sockets will then be retained securely therein.

When the iron is desired to be used by a left-handed person the connection is removed and applied to the threaded opening 23 on the left side of the upright member, the same as described for the right-handed person.

I also provide a threaded plug 45 which engages in either of the threaded sockets 23 and 24 when either of such sockets are not in use so as to prevent injury by contact with the contacting portions of the insert 11.

It will be obvious from the foregoing that I have provided an improved connection for a sadiron which may be used by either a right- or left-handed person as desired, merely by changing the connection of the electric conductor cord to the handle thereof.

What I claim and desire to secure by Letters Patent is:

1. An electric sadiron having a handle of insulating material with an upright portion at the rear thereof, said upright portion having a recess forming a rearwardly opening receptacle and a laterally opening threaded bore communicating with said receptacle, said sadiron having terminals extending into the lower portion of the receptacle, a removable insert substantially filling the receptacle, spaced contact elements in said insert having portions at the lower end thereof for engagement with the terminals, sockets on said contact elements arranged transversely of the insert and opening from the side thereof in alignment with the threaded bore, a flexible cord for connecting the sadiron to an electric power supply, a connection at one end of the cord in the threaded bore in engagement with the side of the insert, prongs on said connection removably engaging in the sockets, and a threaded sleeve member rotatably and slidably mounted on the cord threaded into the threaded bore into engagement with the connection for retaining said connection in engagement with the insert and the prongs in the socket.

2. An electric sadiron having a handle with an upright portion at the rear thereof, said upright portion having a recess forming a rearwardly opening receptacle and a laterally opening threaded bore communicating with said receptacle, said sadiron having terminals extending into the receptacle, a removable insert substantially filling the receptacle, spaced contact elements in said insert having portions engaging the terminals.

nals, sockets on said contact elements arranged transversely of the insert and opening from the side thereof in alignment with the threaded bore, a flexible cord for connecting the sadiron to an electric power supply, a connection at one end of the cord in the threaded bore in engagement with the side of the insert, prongs on said connection removably engaging in the sockets, a threaded sleeve member rotatably and slidably mounted on the cord threaded into the threaded bore into engagement with the connection for retaining said connection in engagement with the insert and the prongs in the socket, and a rubber sleeve engaging over said cord and having one end secured to the threaded sleeve for protecting said cord.

3. An electric sadiron having a handle of insulating material with an upright portion at the rear thereof, said upright portion having a recess forming a rearwardly opening receptacle and laterally opening threaded bores extending through said upright portion and communicating with said receptacle, said sadiron having terminals extending into the lower portion of the receptacle, a removable insert substantially filling the receptacle, spaced contact elements in said insert and having portions at the lower end thereof for engagement with the terminals, sockets on said contact elements arranged transversely of the insert and opening from each side thereof in alignment with the threaded bores, a flexible cord for connecting the sadiron to an electric power supply, a connection at one end of the cord having an offset cylindrical portion forming a shoulder in one of the threaded bores in engagement with the respective side of the insert, prongs on said connection removably engaging in the sockets, a threaded sleeve member rotatably and slidably mounted on the cord threaded into the threaded bore into engagement with the shoulder of the connection for retaining said connection in engagement with the insert and the prongs in the socket, a rubber sleeve engaging over said cord and having one end secured to the threaded sleeve for protecting said cord, and a threaded plug removably mounted in the other threaded bore for closing same.

DONALD LEROY REYNOLDS.
